UNITED STATES PATENT OFFICE.

ELMER J. SMITH AND HARRY W. ATKINSON, OF TARENTUM, PENNSYLVANIA.

DESIGN FOR A LAMP-LENS.

50,922.

Specification for Design. Patented June 12, 1917.

Application filed April 23, 1917. Serial No. 164,067. Term of patent 7 years.

To all whom it may concern:

Be it known that we, ELMER J. SMITH and HARRY W. ATKINSON, citizens of the United States, and residents of Tarentum, in the county of Allegheny and State of Pennsylvania, have invented a certain new, original, and ornamental Design for Lamp-Lenses, of which the following is a specification, reference being had to the accompanying drawing, forming part thereof, in which—

Figure 1 is a front elevation of a lamp lens showing our new design;

Fig. 2 is a back view of the same;

Fig. 3 is an edge view of the same;

Fig. 4 is a cross section of a portion of the lens, on the line 4—4, Fig. 1; and

Fig. 5 is an enlarged section of a portion of the lens on a radial arc, line 5—5, Fig. 1.

We claim:—

The ornamental design for a lamp lens, as shown.

In testimony whereof, we, the said HARRY W. ATKINSON and ELMER J. SMITH, have hereunto set our hands.

ELMER J. SMITH.
HARRY W. ATKINSON.
